UNITED STATES PATENT OFFICE.

FRANK T. COPE, OF SALEM, OHIO, ASSIGNOR TO THE ELECTRIC FURNACE COMPANY,
OF SALEM, OHIO, A CORPORATION OF OHIO.

RECUPERATIVE FURNACE.

Application filed December 21, 1925. Serial No. 76,675.

The invention relates to continuous heat treating or annealing furnaces and more particularly to a furnace for annealing strips or wire strands; and the object of the invention is to provide a furnace in which two strips or strands are continuously moved through the furnace in opposite directions, the incoming cold portion of each strip or strand being preheated by association with the outgoing heated portion of the other strip or strand which is proportionately cooled thereby.

The above and other objects may be attained by constructing a furnace having a central heating chamber communicating at each end with a recuperative hood or tunnel, two strips or strands of material being passed through the furnace, in opposite directions, and in substantial contact with each other, whereby heat will be rapidly transferred from one to the other.

An embodiment of the invention is illustrated in the accompanying drawing, in which

23 Figure 1 is a longitudinal sectional view of the improved furnace, and

Figs. 2 and 3, fragmentary sectional views of hearths especially adapted for treating wire.

30 Similar numerals refer to similar parts throughout the drawing.

The furnace includes the heating chamber 1 in which may be located electric resistors 2 or other suitable heating means, and the recuperating hoods or tunnels 3 communicating with opposite ends of the heating chamber.

In order to anneal or heat treat metal strips or the like, indicated at 4, the material 40 is coiled upon drums 5 mounted at opposite ends of the furnace, the free end of each strip being drawn through the furnace and connected to a power driven drum 6 mounted near the opposite end of the furnace and arranged to be driven by any suitable means such as the motor 7, through the gearing 8.

In order to hold the two strips in sliding contact with one another as they pass through the furnace a spaced pair of rolls 50 9 may be provided at the outer end of each tunnel or hood, through which the strips are passed.

As the drums 6 are rotated to coil the material thereon the strips 4 will be moved through the furnace in the directions of the

arrows shown in Figure 1, the strips contacting with each other throughout the entire length of the furnace.

The material is heated as it passes through the central heating chamber 2 and as the heated portion of each strip passes outward through one of the tunnels or hoods in contact with the incoming cold portion of the other strip it will be seen that it will give up considerable heat to the incoming material, thus preheating each strip before it reaches the heating chamber of the furnace and considerably cooling each strip before it passes out of the furnace.

In Fig. 2 is illustrated a form of hearth or support adapted for use throughout the length of the furnace for the heat treating or annealing of wire.

This hearth or support 10 has the channel support such as the longitudinal groove 11 therein of sufficient width to permit two strands of wire 4^a to pass through the same in opposite directions and in sliding contact with each other, the construction being otherwise the same as illustrated in Figure 1.

A further modification is shown in Fig. 3, which illustrates a tubular guide 12 located through the furnace for passing strands of wire therethrough in opposite directions and in substantial contact with each other.

It is common practice in handling strips or wire strands to stop the operation as the end of each coil is reached and to weld or hook the end of a new coil thereto.

Although the preferred form of the invention is illustrated, it will be seen that the improvement may be carried out by passing one strip or strand into the furnace and then back out of the furnace in the opposite direction and in contact with the incoming cold portion of the strip.

Although the best results are attained by keeping both strips in contact at all times during their passage through the furnace, it will be understood that due to irregularities in the metal strips or to an unequal pull upon one or the other strip, there may be times during the operation when parts of the strips are not in actual contact; nevertheless there would be a direct conduction of heat from the hot strip to the cold strip.

In prior patents two trains of material move in opposite directions through a furnace, the heated train giving up heat by radiation to the cold train, but there is no

direct conduction of heat from metal to metal as in the present case.

I claim:

1. A furnace including a heating chamber, a recuperative hood communicating with each end of the heating chamber, and means for passing strips or strands of material through the furnace in opposite directions and in contact with each other and 10 directly conducting heat from one strip to the other.

2. A furnace including a heating chamber, a recuperative hood communicating with each end of the heating chamber, means 15 for passing two strands of material in op-

posite directions through the furnace and a channel support in the furnace for holding the strands in contact with each other for directly conducting heat from one strip to the other.

3. A furnace including a heating chamber, a recuperative hood communicating with each end thereof and means for passing continuous strips or strands of material through the furnace in opposite directions 20 and directly conducting heat from one strip to the other.

In testimony that I claim the above I have hereunto subscribed my name.

FRANK T. COPE.
